CLAIM

The ornamental design for a hub motor for an electric vehicle, as shown.

DESCRIPTION

FIG. 1 is a perspective view of a hub motor for an electric vehicle showing my new design;

FIG. 2 is another perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom view thereof.

The broken lines shown in the drawings depict portions of the article that form no part of the claimed design.
